UNITED STATES PATENT OFFICE.

WILLIAM E. BLAIR, OF BUFFALO, NEW YORK, ASSIGNOR TO BUFFALO GASOLENE MOTOR COMPANY, OF BUFFALO, NEW YORK, A CORPORATION OF NEW YORK.

STARTING DEVICE FOR EXPLOSION-ENGINES.

1,044,479.

Specification of Letters Patent. Patented Nov. 19, 1912.

Application filed May 18, 1912. Serial No. 698,212.

To all whom it may concern:

Be it known that I, WILLIAM E. BLAIR, a citizen of the United States, residing at Buffalo, in the county of Erie and State of New York, have invented new and useful Improvements in Starting Devices for Explosion-Engines, of which the following is a specification.

This invention relates to a distributing valve which is more particularly designed for use in an air controlling starting device for explosion engines.

It is the object of this invention to provide a valve for this purpose which is simple and durable in construction, which is efficient in operation and will not wear unduly, and which can be adjusted to suit different conditions under which the engine may be operating.

In the accompanying drawings consisting of 2 sheets: Figure 1 is a side elevation of an explosion engine equipped with an air controlling starting device embodying my improved distributing valve. Fig. 2 is a vertical transverse section of the same in line 2—2, Fig. 1. Fig. 3 is a longitudinal section of the distributing valve, on an enlarged scale. Figs. 4, 5 and 6 are transverse sections in the correspondingly numbered lines in Fig. 3. Fig. 7 is a longitudinal section in line 7—7, Fig. 5.

Similar characters of reference indicate corresponding parts throughout the several views.

Although my invention is applicable to explosion engines of various designs that shown in the drawings, for example, comprises a base 1, a plurality of working cylinders 2¹, 2², 2³, 2⁴, preferably four in number, arranged in a row on the base, a main shaft 3 adapted to be rotated by the explosive and air pressures in the cylinders and a cam shaft 4 arranged lengthwise of the base and forming part of the means for transmitting motion from the main shaft to the fuel inlet and exhaust valves of the engine whereby the same is operated explosively.

The compressed air or other fluid under pressure is preferably stored in a tank or reservoir 5 and may be charged by an air pump having its barrel 6 connected with the storage tank by a pipe 7 containing a check valve 8, and its plunger 9 operated by an eccentric 10 on the main shaft and a strap

11 surrounding the eccentric and connected with the plunger, as shown in Figs. 1 and 2. Excess pressure in the storage tank is prevented by providing the same with a safety valve 12 which blows off automatically when the pressure in the tank exceeds a predetermined limit. The compressed air is withdrawn from the storage tank through a delivery pipe 13 containing a check valve 14.

The form of valve shown in Figs. 3—7 for distributing the compressed air successively to the several engine cylinders in accordance with my invention is constructed as follows: This distributing valve comprises a casing having a body 15 which contains a cylindrical air distributing chamber 16 in its front part and a cover or head 17 which closes the front end of the chamber and is detachably connected with the body by bolts 18, as shown, or otherwise. The body is supported from the frame of the engine by a bracket 19 and the same is provided with an axial bearing 20 which opens into the inner end of the cylindrical chamber thereof and receives the adjacent end of the cam shaft 4. The delivery pipe 13 of the air storage tank communicates with the front end of the distributing chamber 16, preferably, by connecting this pipe with the central part of the head thereof. The body of the distributing valve is provided in the bottom of its distributing chamber with a plurality of distributing ports 21, 22, 23, 24 one for each of the four engine cylinders, these ports being arranged equidistant in an annular row concentrically around the axis of the cam shaft and opening at their outer ends through the sides of the valve body 15 where they are connected respectively with the four engine cylinders by distributing pipes 25, 26, 27, 28.

29 represents a rotatable valve disk engaging with the bottom of the valve chamber and provided with a single curved port 30 whereby, on turning this disk the interior of the valve chamber is placed in register with the distributing ports 21, 22, 23, 24 successively. On its rear side the valve disk is provided centrally with a coupling shank or stem 31 of cylindrical form which is journaled in the inner end of the bearing 20. This valve disk is compelled to turn with the cam shaft but is free to move axially toward its seat on the bottom of the valve chamber in case of wear by a coupling which

preferably consists of a mortise 32 formed on the end of one of these parts and a tenon 33 engaging with said mortise and formed on the opposing end of the other of said parts. As shown in Figs. 3 and 7 the mortise is formed on the end of the cam shaft and the tenon is formed on the stem of the distributing valve disk. By this means a driving connection is maintained between the cam shaft and the distributing valve disk whereby the latter is always free to engage fully against its seat so as to prevent leakage and at the same time this disk is always turned by the cam shaft and remains in the proper position relatively to the distributing ports.

In order to permit of regulating the timing of the distributing valve disk to suit different conditions a regulating device is provided comprising a regulating disk 34 engaging its rear side with the front side of the valve disk while the front side of the regulating disk engages at the margin thereof with the cover or head of the valve casing. The regulating disk is provided with a plurality of regulating ports 35, 36, 37, 38 which are arranged in an annular row and which are adapted to be arranged either in alinement with the distributing ports 21, 22, 23, 24, respectively, or out of alinement with said mentioned ports.

As the valve disk turns its port 30 operates to place the companion ports of the regulating disk and valve casing successively in communication with each other in pairs so that the compressed air from the storage tank entering the valve chamber passes from the latter successively through the several pairs of corresponding ports in the regulating disk and casing and through the valve disk and is conducted by the companion distributing pipes successively to the firing ends of the several working engine cylinders. A pressure is thus produced successively against the pistons in the several engine cylinders whereby the engine is started preparatory to continuing the running of the same by explosive fuel.

Upon turning the regulating disk so that its ports are in line with those of the valve casing the port of the valve disk will communicate simultaneously with the companion regulating and distributing ports of the several pairs and thereby admit compressed air to the several engine cylinders at what may be regarded as the normal time under the conditions which the engine is working.

When the regulating ports and distributing ports of each pair are in full register the same are placed in communication during the longest period of time by the curved port of the valve disk so that the air pressure is utilized to the maximum extent for starting the engine. Upon turning the

regulating disk backwardly the port of the valve disk will register with the regulating ports in advance of the normal time and cut the same off earlier from the corresponding distributing ports, while upon turning the regulating disk forwardly the registration of the port of the valve disk with the ports of the regulating disk will be delayed beyond the normal and the cutting off of the compressed air supply to the engine cylinders will be correspondingly delayed. The admission of the compressed air to the cylinders of the engine can by this means be timed and the quantity of air controlled as best suits the engine on which this device is installed. When the regulating disk is turned so that its ports are either forwardly or backwardly out of alinement with the distributing ports the period of time during which the corresponding regulating and distributing ports are placed in communication with each other is reduced and the admission of compressed air to the engine cylinders is therefore reduced or throttled accordingly.

Various means may be employed for adjusting the regulating disk and holding the same in position after adjustment, those shown in the drawings being suitable and consisting of one or more longitudinal locking pins 39 arranged on the head or cover of the casing adjacent to the bore thereof and one or more sets of locking notches or openings 40 arranged circumferentially in the periphery of the regulating disk and each pin adapted to be engaged with one or the other of the notches of one of the sets, according to the particular timing best suited to produce the desired result. This distributing valve is very simple in construction, the same is not liable to leak or get out of order and the same can be easily dismembered and assembled for inspection, adjustment and repairing.

I claim as my invention:

1. A fluid controlling starting device for explosion engines comprising a valve casing having a port, a movable valve disk arranged in said casing and having a port adapted to register with the port of the casing, and an adjustable regulating disk arranged in the casing on that side of the valve disk opposite to the port of the casing and having a port adapted to register with the port of the valve disk.

2. A fluid controlling starting device for explosion engines comprising a valve casing having an internal valve seat and an annular row of fluid distributing ports, a rotatable valve disk arranged in the casing and engaging its rear side with said valve seat and having a port adapted to register successively with said distributing ports, and an adjustable regulating disk arranged in said casing and engaging with the front

side of said valve disk and having a plurality of regulating ports which are adapted to be placed in communication with the respective distributing ports by the port of 5 said valve disk.

3. A fluid controlling starting device for explosion engines comprising a valve casing having an internal valve seat and an annular row of fluid distributing ports, a rotatable valve disk arranged in the casing and engaging its rear side with said valve seat and having a port adapted to register successively with said distributing ports, an adjustable regulating disk arranged in said 10 casing and engaging with the front side of said valve disk and having a plurality of regulating ports which are adapted to be placed in communication with the respective distributing ports by the port of said 15 valve disk, and means for adjusting said regulating disk about its axis.

20 4. A fluid controlling starting device for explosion engines comprising a valve casing having an internal valve seat and an annu-

lar row of fluid distributing ports, a rotatable valve disk arranged in the casing and engaging its rear side with said valve seat and having a port adapted to register successively with said distributing ports, an adjustable regulating disk arranged in said 25 casing and engaging with the front side of said valve disk and having a plurality of regulating ports which are adapted to be placed in communication with the respective distributing ports by the port of said valve 30 disk, and means for adjusting said regulating disk about its axis comprising a locking pin arranged on the casing and adapted to engage with one or another of a circumferential row of notches in the periphery of 35 40 said regulating disk.

Witness my hand this 16th day of May, 1912.
